UNITED STATES PATENT OFFICE.

VASLE VINCIN, OF HUMBLE, TEXAS.

GLOVE.

Application filed October 22, 1921. Serial No. 509,637.

To all whom it may concern:

Be it known that I, VASLE VINCIN, a citizen of the United States, residing at Humble, in the county of Harris and State of Texas, have invented certain new and useful Improvement in Gloves, of which the following is a specification.

This invention relates to new and useful improvements in gloves.

10 One object of the invention is to provide a glove without a seam between the thumb and first finger.

Another object is to provide a glove whose thumb, first finger and the palm and front 15 part of the other fingers are all formed of a single piece of material, thus having few seams to rip and adding durability to the glove.

With the above and other objects in view 20 this invention has particular relation to certain novel features of construction, and use, an example of which is given in this specification and illustrated in the accompanying drawings, wherein—

25 Figure 1 shows a palm view of the glove, Figure 2 shows a back view.

Figure 3 shows a pattern on which the part of the glove forming the palm, thumb and first finger is cut, showing, in dotted 30 lines where the material is to be slit in the formation of the other three fingers, and Figure 4 shows said pattern folded preparatory to stretching the thumb into form.

Referring more particularly to the drawings, the numeral 1 designates the palm 35 of the glove. The material of which the palm is made is extended forming the entire thumb 2, and first finger.

The material of the thumb is sewed along 40 the outside opposite the crotch forming a seam which continues along said outside to the wrist of the glove and the seam of the first finger is along the side toward the second finger so that there will be no seam 45 between the thumb and adjacent finger. This is the point where the material is subjected to the greatest strain and a seam between the thumb and first finger soon rips,

particularly in the case of workmen's gloves. In manufacture the material of which the palm, thumb and first finger of the glove is made is softened by soaking in water and then formed as shown in Figure 4 and then stretched to give the material of the thumb the proper shape. The back parts of the 50 second third and fourth fingers are formed of the separate strips 4, 5 and 6 which are sewed in place along the sides of said fingers. All of the rest of the hand part of the glove is formed of a single piece of material 55 cut in the form of the patterns shown in Figures 3 and 4.

What I claim is:—

1. A glove whose palm, thumb, first finger and the front part of the other fingers are formed of a single piece of material, and the backs of all of the fingers, excepting the first finger are formed of separate strips of material, the material between the thumb and first finger being formed into a crotch, 60 and the edges of the thumb material being sewed together forming a seam along the outside of the thumb to the wrist of the glove.

2. A glove, the material of the palm of 75 which is extended forming the entire thumb and the entire first finger, and the front part of the other fingers, the material of which the first finger is formed being sewed along the side next to the second finger, there 80 being no seam between the thumb and first finger, said material between the thumb and first finger being stretched to form a crotch of the contour of a corresponding part of the hand of the wearer, the material of the 85 thumb being sewed along the side thereof opposite the crotch forming a seam along said side to the wrist of the glove.

In testimony whereof I have signed my name to this specification in the presence of 90 two subscribing witnesses.

VASLE VINCIN.
